ARTICLE OF FURNITURE

William R. Brown, Cleveland, Ohio

Application October 20, 1954, Serial No. 463,486

2 Claims. (Cl. 5—14)

2

Figure 2 is a view similar to that of Figure 1 showing the bed unit moved forwardly of the main frame so that the article of furniture may be used as a bed;

Figure 3 is a perspective view of the spring and mattress holding bed unit;

Figure 4 is a perspective view of the seat frame unit;

Figure 5 is a section taken on line 5—5 of Figure 4;

Figure 6 is a section taken on line 6—6 of Figure 4;

Figure 7 is a section taken on line 7—7 of Figure 3;

Figure 8 is a section taken on line 8—8 of Figure 3;

Figure 9 is a detail view of a retracting mechanism mounted on the bed frame; and

Figure 10 is a broken away sectional view of one end of the article of furniture taken on line 10—10 of Figure 1.

15 In carrying out my invention according to an embodiment thereof illustrated in the accompanying drawings, I provide a main frame comprising a back 1 and a pair of end members 2 extending forwardly from the opposite ends of the back member 1 and in substantially parallel relation to each other, these end members having a rear portion which is substantially coextensive in height to the height of the back member and extending forwardly forming arm portions 3 of reduced height.

The main frame also includes a base frame substantially 25 rectangular in form and including the side rails 4, a rear rail 5, and a forward rail 5', the end members 2 being secured to and supported on the side rails 4 and attached to the back 1. The main frame is provided with casters or rollers 6 on which the main frame and auxiliary frame 30 carried thereby are supported thereby rendering the article of furniture entirely portable, as a davenport.

An auxiliary frame is indicated generally at 7 and is 35 adapted to carry the spring 8 and the mattress 9, this auxiliary frame being supported by forward casters or rollers 10 which engage the floor, as do the casters 6, and rollers 11 carried by the base members 12 of the auxiliary frame and engage and roll upon the end rails 4. The auxiliary frame is also provided with rollers 13 which are mounted on substantially vertical axes and which engage the end plates 14 on opposite ends of the davenport. The plates 14 extend forwardly from the back wall and are carried on the inner surfaces of the end members 2, respectively, and are adapted for cooperation with certain linkage mechanism which will be described more fully 40 hereinafter.

In using the combination article of furniture as a davenport, the backrest 15 is extended as illustrated in Fig. 1 but when it is desired to use the article of furniture as a bed, as illustrated in Fig. 2, it will be noted that the 45 backrest 15 is caused to move to a position rearwardly and upwardly of that illustrated in Fig. 1 and is hidden from view by the seat frame 16, merely by raising the seat cushion about its pivot carried in the backrest.

The two respective end plates 14 carried on the inner 55 surfaces of the end members 2 are fixed to these end members respectively and are provided with substantially vertical slots 17 extending downwardly from the rear top edge of the plates and are also provided with stepped track portions formed along the intermediate and upper 60 edges of the respective plates 14, these track portions comprising a forward lower level horizontal portion 18 and a land 18' terminating rearwardly in a rearwardly inclined riser 19 and thence terminating rearwardly in the higher level top edge portion 20 which in turn extends 65 rearwardly and terminates at its rear end in the forward wall 21 of the slot 17. This slot extends downwardly and terminates in a bottom wall 22, the rear slot wall being indicated at 22', which terminates in a rearwardly extending horizontal edge 20' substantially parallel with 70 but at a lower level than the edge 20.

The backrest 15 and the seat cushion 16 are pivotally connected together at 23, the seat cushion 16 having a

My invention relates to convertible combination furniture which in the present instance is in the form of a davo-bed.

It is one of the objects of this invention to provide an article of convertible furniture, such as a combination davenport-bed which is of extremely simple construction and which is designed to conserve space, therefore making the article of furniture particularly suitable for use in hotels, motels, and other establishments of this general type, although the device is equally well suited for domestic use in apartments and in the home.

It is an important object of this invention to provide a mechanism in an article of furniture of this type wherein a transition or conversion from a davenport to a bed and vice versa may easily be effected.

It is another object of this invention to provide a convertible davenport-bed combination having a davenport backrest which readily may be moved out of sight by virtue of mechanism associated with the main frame, seat cushion and with the backrest and which may be easily actuated by lifting the seat cushion about its pivot.

Another important object of this invention is a positive controlling mechanism for converting the article of furniture from a bed to a davenport or vice versa.

Another object of the invention is the elimination of extraneous projections or portions extending beyond the main frame thereby enabling the furniture unit to be used in restricted areas.

Another object of the invention is an article of furniture of this type which is portable in its nature.

A still further object of the invention is the provision of an article of furniture of this type which is sturdy in construction yet which is extremely comfortable in use either as a bed or as a davenport.

Another object of the invention is a new and improved seat construction affording a high degree of comfort in use, while providing a structure forming a part of the means by which conversion from a davenport to a bed and vice versa may easily be accomplished.

A still further object of the invention is the provision of a davo-bed of improved and sturdy construction combining durability, comfort and good appearance.

Another important purpose of the invention is that the bed can be made up completely in advance of the time it is desired for use, as such, and that it can be made available for such use easily and quickly.

Other objects and advantages of this invention will become more apparent as the following description of an embodiment thereof progresses, reference being made to the accompanying drawing in which like reference characters are employed to designate like parts throughout the same.

In the drawings:

Figure 1 is a transverse section through an article of furniture embodying my invention, the bed unit being slidable to the right in Figure 1 as indicated in Figure 2. In the position of Figure 1, the article of furniture is used as a davenport;

portion or arm 16' extending rearwardly of the pivot 23 and terminating in a freely rotatable roller 24 which is adapted to enter the substantially vertical downwardly projected slot 17 and to ride therein during the conversion of the article of furniture from a davenport to a bed, or vice versa. Rollers 25 are mounted for free rotation on the pivot pins 23 and are arranged to travel along the stepped upper edge of the end plates 14.

Connected with the axis of the roller 24 is a lever 26 pivoted to the end plates at 27 and having pivotal connection at its opposite end at 28 with an arm 29 which extends upwardly and at its upper end is pivotally connected at 30 with the hinge 31. The hinge 31 is secured at opposite sides to the cover sections 32 and 33, the section 33 being hinged to the back of the backrest at 34 and the section 32 being pivotally connected at 35 to the back member 1. It will be seen that as the seat cushion is rotated about the pivot 23 from the position shown in Fig. 1 to the position shown in Fig. 2, that the roller 24 will engage the walls of the slot 17 and move in a downward direction along the slot, thus rocking the lever 26 to transmit an upward longitudinal movement of the arm 29 and to break the cover sections 32 and 33 in the hinge 31 so that these sections will automatically assume the folded position shown in Fig. 2. When the cover sections are in the position shown in Fig. 1, they will serve as a support for the backrest 15. As the seat cushion 16 is raised about the pivot 23 and as the roller 24 descends into the slot 17, a roller 25 will travel up riser 19 and along the horizontal edge of the end plate portion 20 until the seat cushion is in substantially vertical position whereupon the weight of the cushion and backrest is carried by roller 24 which then is resting on the slot bottom wall 22, thus lifting the backrest and the seat cushion upwardly during its rearward travel.

Also connected to the pivot 23 is a link 36 having an elongate slot 37 along which the pin 38 carried by the end plate 14 travels during the rearward and upward movement of the seat cushion and backrest assembly.

A link 39 is pivoted at one end to the pivot 23 and at its other end to a second link 40, as at 41. This second link is pivotally mounted at its upper end at 42 to a bracket 43. A bracket 44 which is mounted on the inner wall of the back member 1, as is the bracket 43, is pivotally connected at 45 to a link 46. The link 46 is provided with a shoe 47 for sliding contact with the rear surface of the backrest 15. The links 46 and 40 are connected together by an intermediate link 48 by means of pivots 49 and 50.

As illustrated in Fig. 1, in using the article of furniture as a davenport with the backrest 15 in its forward inclined position, the frame rails of seat cushion 16 will lie in a substantially horizontal position and will be supported at their forward ends on the top rail 51 of the upper hinged section of the auxiliary front frame member and in depressed position under load are supported at their rearward ends by means of the rollers 25 resting on the land 18', the major portion of the seat cushion being disposed to lie upon the mattress 9 thereby affording a maximum of comfort to the user in sitting upon the davenport, and at the same time providing a resilient front edge support for the seat cushion, as will be explained more fully hereinafter.

When the combination furniture is used as a bed, as in Fig. 2, and the operator has lifted the seat cushion to the position shown in this figure, the backrest will be caused to move rearwardly and upwardly along the end plates 14 with the seat cushion and will be hidden from view behind the seat cushion, the linkage-leverage mechanism being illustrated in this figure in the position it will assume under such circumstances, that is, a somewhat retracted position as compared with that shown in Fig. 1 when the article of furniture is used as a davenport.

Referring more particularly to Fig. 4 of the drawings, I have illustrated in that figure one form of seat cushion

frame which, as illustrated, includes a pair of longitudinal frame members 52 and 53 spaced apart in substantially parallel relation and connected at their respective ends by end frame members 54 and 55, each of the frame members being formed of a relatively thin strip of metal which is of sufficient thinness to be resilient and flexible enough for comfort under load. The rear longitudinal member is provided at its ends with upturned flanges 56 which extend outwardly beyond the respective transverse end members 54 and 55. These flanges are each provided with an opening 57 to receive the pivot pin 23 which also passes through aligned openings in the hinge sections 59 and 60 carried by the backrest frame and the seat frame, respectively. The spaced hinge sections 60 are disposed on opposite sides of a frame rail 61, the forward end of which is secured to the forward brackets 62 as at 63. This is clearly indicated to the left in Fig. 4, the right hand end of Fig. 4 not showing this part of the seat frame for purposes of clearness. The hinge sections 59 are mounted on opposite sides of the backrest frame members 64 and are hinged to the sections 60 by the hinge pins 23, as described above, the hinge pins 23 rotatably carrying at their outer ends respectively the rollers 25 which serve to support the backrest and the rear portion of the seat frame on the end plates 14.

The seat cushion frame is also provided with a peripheral reinforcing wire on its top surface, as indicated at 65, this peripheral frame wire being anchored to the longitudinal and transverse frame members at intervals by means of hog rings 66 which are carried in openings 67 in the frame members and embrace the peripheral wire 65 as indicated in detail in Fig. 6. I have also provided a plurality of transverse wires 68 spaced at intervals lengthwise of the frame which together with the spaced longitudinal wires 69 provide a supporting grid for the seat cushion carried by the frame. The forward ends of the wire 68 are hooked over the peripheral wire, as at 70, while the rear ends of the transverse wires 68 terminate in a headed portion 71 engaging one end of a compression spring 72 through which the wires 68 pass in an axial direction so that when a load is placed upon the seat cushion and thence upon the transverse wires, the spring 72 will be placed under compression. The sprung and headed ends of the transverse wires 68 and longitudinal wires 69 are carried within a housing 73 which is slipped over the peripheral wires 65. In Fig. 5 is shown a detail of one of the compression units and while this figure is taken on line 5-5 of Fig. 4 showing the compression unit mounted on one of the transverse frame members, it is understood that these units are identical in construction to those mounted on the longitudinal frame member 52. The compression spring units mounted on the two end frame members 54 and 55 support the longitudinal wires 69 at their respective ends and when a load is imposed upon the frame grid formed by the wires 68 and 69, the respective coil springs 72 in the spring units will be placed under compression as the wires are flexed downwardly under load, the springs 72 serving to return the longitudinal wires 69 and, in the case of the transverse wires 68, to a normal position such as indicated in Fig. 4 when the load is removed from the seat cushion.

To further provide for flexibility of the seat frame under load and yet to sustain the frame in its normal unflexed condition when not under load and to give rigidity to front frame members 53 when raised from horizontal toward vertical position, I have provided reinforcing members along the front frame member 53 indicated at 75, these members being arranged in end to end relation and being connected together by flexible straps 76. Each of the reinforcing members 75 is secured to the front longitudinal frame member by means of the holding and clamping members 77.

Fig. 4 shows a preferred type of seat frame construction and for purposes of clearness, the cushion portion 75 of the seat is removed.

In Figs. 3, 7, 8 and 9, I have illustrated a form of construction for the slidable auxiliary frame 7 which carries the davo-bed spring 8 upon which is superimposed the mattress 9 and when the article of furniture is used as a davenport, the major portion of the seat 16 will be supported upon the mattress, the forward edge of the seat and its frame resting upon the forward upper hinged-flexible section of the auxiliary frame, as shown in Fig. 1.

Describing more in detail the construction of auxiliary frame, the same comprises a rear wall 80, opposite end walls 81 and 82 extending upwardly beyond the top of the rear wall 80. A rigid front wall 83 connects the forward ends of the end walls 81 and 82 along the lower portion thereof. The wall 83 is preferably of rigid construction to which is hingedly connected an upper flexible front wall section, as at 84. The walls 80, 81, 82, 83 forming the rectangular auxiliary frame are supported on a base frame indicated by the rear and front frame members 85 and side frame members 86, there being an intermediate transverse frame member 87 connecting the rear and front frame member 85 as shown more clearly in Figs. 7 and 8, this intermediate transverse frame member 87 not only serving to strengthen the auxiliary frame, but also to carry certain latch and control means which will be described more fully hereinafter.

As stated above, the forward wall of the auxiliary frame is composed of a rigid lower frame member 83 and an upper resilient frame member hingedly connected thereto, as at 84, and which comprises a pair of rails 51 and 88 connected together near their opposite end portions by straps 90 which may be of canvas or other suitable flexible material and which limit the movement of the rails 51 and 88 away from each other. In Fig. 3, the rail 51 is shown as comprising a pair of rail members placed end to end, the adjacent ends being pivotally connected by hinge 89 attached thereto by bolts 89' and 89" in a manner to permit the divided rail 51, when in the position illustrated in Fig. 1, to "break" downwardly under a load greater than that of the forward portion of seat cushion 16 which rests on the said rail 51 in davenport position. By this construction, the composite rail 51, in davenport position, is rendered resilient under load applied to either end or simultaneously to both ends of said rail if the load is sufficient to depress the springs 91 and 92 and is both resilient and flexible if the load is applied to the center of said rail. The adjacent ends of the rail 51 substantially meet as at 51', as illustrated in Fig. 3, when the rail sections are not under load, but when in position shown in Fig. 1, they separate at their under and inner areas 51' due to movement about the bolts 89' and 89" when the center portion of the member 51 is placed under downward load in excess of the forward portion of cushion 16. This rail 51 is rigid, beyond horizontal position, to pressure in the opposite direction. The rails 51 and 88 are maintained in spaced relation, as indicated in Fig. 3, by resilient means, such as the looped springs 91 and 92 which normally exert a tension to spread the rails 51 and 88 apart, but which may be placed under compression when the flexible hinge section is in its raised position, as in Figs. 1 and 2 when a load greater than the weight of the seat cushion is imposed upon it. The resilient members 91 and 92 are mounted under compression by means of the brackets 93 secured to the respective rails 51 and 88, the intermediate coil portions of these resilient members being indicated at 94 and serving to maintain the resilient members under compression forces normally urging the rails 51 and 88 apart.

When the hinged upper section of the front member of the auxiliary frame members and resiliently spaced rails 51 and 88 are in the position shown in Fig. 1, it is desirable to provide latching means to maintain the hinged resilient rails 51 and 88 in this position during use of the article of furniture as a davenport and I have therefore provided a pair of spring projected bolt type

latches indicated at 95 mounted on opposite ends of the upper rail 51 and adapted to enter the vertically elongated latch notches 96, elongated to permit upward and downward movement of flexible rail 51 when the frame member is raised to its uppermost position, and to remain engaged with the latch notches until released by means of a releasing lever or arm 97 pivotally mounted at 98 to the inner surface of the upper rail 51. Connecting rods 99 extend from opposite sides of the pivot 98 and are connected with the respective spring urged bolts 95. In Fig. 7 the hinged front frame section 51-88 is shown in solid lines latched in its upper position but by shifting the lever 97 in a clockwise direction, as in Fig. 3, it will be seen that the latches will be retracted from engagement with the notch walls 96 and the upper flexible section of the front frame member will be allowed to assume the down position shown in Fig. 3, as when the article of furniture is to be used as a bed.

Referring now more particularly to Fig. 7 which shows the auxiliary frame retracted in the main frame when the article is to be used as a davenport wherein the hinged front upper flexible section of the frame is shown in full lines in the uppermost position and in dotted lines in position when the auxiliary frame is extended to be used as a bed, it will be noted that I have provided a latching means carried by the intermediate transverse frame member 87, on one side thereof, as shown also in Fig. 3, whereby the extended position of the auxiliary frame may be limited and whereby the frame may be releasably held in retracted position. I provide a stop 100 rigidly secured to the intermediate base frame member 101 in the path of movement of the latch member 102 pivotally carried by the intermediate transverse frame member 87 as at 103 to limit the extended position of the frame as shown in dotted lines. Counterclockwise rotation of the latch 102 is limited by means of the pin 104, there being a coiled spring 105 mounted on the pin or axis 103 and having oppositely extended arms, one engaging the top surface of the pivoted member 102 and the other securely anchored to the intermediate frame member 87 to exert a normal tension on the member 102 to tend to retain it in the full line position shown in Fig. 7. The latch 102 is connected to the hinged front auxiliary frame member 88 by means of a cable or chain 106 connected at one end to the latch member as at 107 and movably supported along one side of the intermediate frame member 87 by means of pins or pulleys 108 and 109, forward pulley or pin 109 being provided to receive the cable on its under surface, the cable 106 being threaded through an eye or pulley 110 and connected at its other end to the front frame member 88, as at 111.

It will be seen from the full line position shown in Fig. 7 that when the auxiliary frame is retracted in the main frame, the hinged front frame member is in uppermost position and latched at 95 to the side walls 81 and 82. The latch 102 will be urged downwardly by the spring 105 behind the stop 112 which in this position engages the front edge of the latch member 102. When the latches 95 are released and the front frame members 51 and 88 are rotated forward and downwardly of the auxiliary frame, as shown in dotted line position, as when the auxiliary frame is extended from the main frame to bed position, the movement of the front hinged frame member to the dotted line position from the full line position will cause the cable 106 to be pulled forwardly, thus raising the latch 102 out of engagement with the stop 112 carried in the transverse main frame member 101, thus permitting unobstructed forward motion of the auxiliary frame in its limited forward direction until the latch 102 engages the stop 100 carried by the intermediate base frame member 101. When the hinged front section 51-88 is raised to a latched position and the extended auxiliary frame is again pushed back into its nested position in the main frame, the inclined lower edge of the latch 102 will en-

gage the stop 112 and will ride over the same and again assume the position shown in Fig. 7 in full lines.

In Figs. 8 and 9, I have illustrated the means whereby the auxiliary frame is normally urged forwardly of the main frame, that is, to the bed position, when the auxiliary frame is unlatched from its retracted position as shown in Fig. 1.

This means comprises a simple mechanism including a spring urged drum carried within the casing 120 which is mounted forwardly on a side of the intermediate base frame member 101 opposite to that side corresponding to the side of the intermediate auxiliary frame member 87 carrying the latch 102. On the drum is wound a strap or band 121 extending from the housing through an opening 122 and terminating forwardly in an end 123 secured to a depending arm 124 which is secured at its upper end to the intermediate auxiliary frame member 87 as at 125. It will be seen from Figs. 8 and 9 that since the band or strap 121 is normally under tension by means of the spring urged drum within the casing 120 that when the hinged front rails 51 and 88 are held in upward position by the latches 95 and the auxiliary frame is retracted and retained in retracted position by means of latches 102 as shown in full lines in Fig. 7, the spring urged drum within the housing 120 is caused to be wound under greater tension since the band or strap 121 will be in fully extended position but when the latches 95 are released by operating the releasing lever 97 and hinged front rails 51 and 88 are rotated to lower position releasing latch 102, the tension of the spring urged drum will cause the strap 121 to be retracted within the housing and around the drum, thus pulling the auxiliary frame forwardly along the base frame upon which the rollers 11 ride. To return the auxiliary frame to its nested position with respect to the main frame, the user merely raises the hinged rails to their upper and latched position, pushes against the forward portion of the auxiliary frame until latch 102 is urged downwardly back of stop 112 by means of the spring 105.

Various changes may be made in the details of construction and arrangement of parts of the invention without departing from the spirit thereof or the scope of the appended claims.

I claim:

1. An article of furniture selectively convertible for use as a bed and davenport comprising a main supporting frame having vertically disposed end and rear walls, a spring and mattress carrying auxiliary frame slidably supported by and guided within the main frame permitting forward and rearward movement thereof along said main frame, a backrest pivotally and slidably supported in the main frame, end plates within the main frame and supported on said end walls, a seat frame pivotally con-

nected with said backrest, and means operatively connected with said backrest, said seat frame, said end plates and said main frame rear wall to move the backrest rearwardly toward the main frame rear wall when the seat frame is moved about its pivot in one direction as when converting the article of furniture for use as a bed, and supporting rollers having an axis common to the pivotally connected seat frame and backrest, said end plates having aligned vertically stepped supporting surfaces for said rollers and aligned guideways rearwardly of said stepped surfaces, a guide roller on each side of said seat frame disposed for travel in said guideways, the axes of said guide rollers and said backrest supporting rollers having pivotal connection with said backrest operating means.

15 2. An article of furniture selectively convertible for use as a bed and davenport comprising a main supporting frame having vertically disposed end and rear walls, a spring and mattress carrying auxiliary frame slidably supported by and guided within the main frame permitting forward and rearward movement thereof along said main frame, a backrest pivotally and slidably supported in the main frame, end plates within the main frame and supported on said end walls, a seat frame pivotally connected with said backrest, and means operatively connected with said backrest, said seat frame, said end plates and said main frame rear wall to move the backrest forwardly away from said main frame backwall when the seat frame is moved about its pivot in a forwardly direction as when converting the article of furniture from use as a bed to use as a davenport, and supporting rollers having an axis common to the pivotally connected seat frame and backrest, said end plates having aligned vertically stepped supporting surfaces for said rollers and aligned guideways rearwardly of said stepped surfaces, a guide roller on each side of said seat frame disposed for travel in said guideways, the axes of said guide rollers and said backrest supporting rollers having pivotal connection with said backrest operating means.
